SWITCH

Ernst Walter Rickmeyer, Elmhurst, Ill., assignor
to Jefferson Electric Company, Bellwood, Ill., a
corporation of Illinois

Application March 15, 1939, Serial No. 261,992

2 Claims.

(Cl. 200—1)

My invention relates to switches, and more particularly to a manually operable switch which utilizes a liquid contacting medium for controlling an electrical circuit.

Because of their long life, freedom from open arcs, ease of operation and high current carrying capacity, mercury tube switching elements are very desirable for many purposes in electrical control. Switches having a liquid or mercury contacting medium, as distinguished from switches having mechanical circuit breaking elements, depend upon the slope or disposition of the liquid or mercury containing portion of the switch for determining circuit openings and closure. It is, therefore, desirable that certain features and adjustments be provided in a switch embodying a liquid or mercury circuit controlling medium which are not of importance in a switch having mechanical circuit controlling elements.

It is an object of my invention to provide a switch in which a mercury contact element is utilized for controlling an electrical circuit and which is adapted to be adjusted for mounting at any one of a plurality of angles.

Another object of my invention is to provide a switch having a liquid circuit making and breaking medium and which is particularly adapted for mounting on a control panel or in an enclosure with an operating member exposed.

Another object of my invention is to provide a switch having a plurality of mercury switch elements in predetermined relative positions and actuated thereby for controlling a plurality of electrical circuits in predetermined timed relation and sequence.

Another object of my invention is to provide a switch biased to one operating position and operable to other positions, said switch having means effecting quick movement to and from each of said other positions.

Another object of my invention is to provide a switch utilizing one or more mercury switching elements and which is easily manufactured and assembled, as well as adaptable to a wide variety of uses and mounting positions.

Other objects and advantages of my invention will be apparent from the following description wherein reference is made to the accompanying drawings and a preferred embodiment of my invention is clearly described and illustrated.

In the drawings:

Fig. 1 is an exploded view of a switch embodying a preferred form of my present invention;

Fig. 2 is a fragmentary view of a part of the switch shown in Fig. 1 with the parts shown in their assembled relation;

Fig. 3 is a fragmentary sectional view taken substantially on line 3—3 of Fig. 4 and in the direction of the arrows;

Figs. 4 and 5 are front elevations of an assembled switch such as that shown in Fig. 1, which indicate operating positions of the switch and show the switch in its relation to panels having different slopes;

Figs. 6 and 7 are views similar to those indicated in Figs. 4 and 5 but illustrate a switch which is modified in certain details;

Figs. 8 and 9 are elevational views of a switch embodying a modification of my present invention and illustrate different mounting positions of the switch;

Fig. 10 is a fragmentary sectional view taken substantially on line 10—10 of Fig. 8 and in the direction of the arrows; and

Fig. 11 is a fragmentary view of a portion of the switch illustrated in Figs. 8 and 9 and illustrates an operating position of the switch different from that illustrated in Figs. 8 and 9.

Having particular reference to Figs. 1 to 5, inclusive, the switch has a base or mounting bracket 20 having an opening 21 therein in which a stud 22 is rotatably mounted.

The base or mounting bracket 20 has integral lugs 23 thereon for securing it to a mounting panel or support 24 by screws or other suitable fastening means 25. The stud 22 is so shaped that it has a shoulder 26 that rests against one surface of the base or mounting bracket 20 with a portion 27 rotatably mounted in the opening 21 and pressed into an opening 28 in an operating member 29 so that the stud 22 is moved with the operating member 29. The stud 22 also has a portion 30 of reduced diameter onto which an adjusting plate 31 is pressed into position adjacent to the surface of the operating member 29 opposite the base or mounting bracket 20. On this same portion 30 of reduced section of the stud 22 a bracket 33 is also secured as by riveting the stud at 34. The portion 30 of the stud 22 extends through openings 34' and 35 in the adjusting plate 31 and bracket 33, respectively. The angular position of the bracket 33 is preadjusted with respect to the adjusting plate 31 by rotating the bracket on the portion 30 of the stud and securing it in the desired pre-adjusted position by a pin 35' or other suitable means which extends through an opening 36 in the bracket 33 and into any one particular or desired opening of a series of openings 37 in the adjusting plate 31. The pin or fastening means 35' is preferably riveted or otherwise firmly secured in position after the proper angular adjustment of the bracket 33 has been made. It is understood that the angular position of the bracket 33 may be secured with respect to the adjusting plate 31 by punching or otherwise securing the parts after their relative positions have been determined. In some instances the stud 22 has a portion 39 of reduced section on the end thereof opposite the

portion 39 for accommodating a second bracket 40 which is secured thereto as by riveting the stud at 41.

In the preferred embodiment of my switch a portion 42 of the base or mounting bracket 20 adjacent to the opening 21 is offset from the rest of the surface of the base or mounting bracket to reduce the frictional engagement between the base or mounting bracket and the operating member 29.

To effect adjustment of the angular position of the bracket 33 and compensate for the angle or slope of the panel 24 upon which the switch is mounted, a plurality of openings such as 44, 45 and 46 are provided in the adjusting plate 31. The positions of the openings, such as 44, 45 and 46, are predetermined for certain standard mounting panel slopes, although in certain instances where more intermediate positions might be desirable the openings 44, 45 and 46 may be replaced by an open slot. To effect the angular adjustment of the adjusting plate 31 and bracket 33 a screw 47, or other suitable fastening means, extends through the desired opening 44, 45 or 46 and is threaded into an opening 48 in the operating member 29, or otherwise secured thereto. It will be understood that by proper pre-adjustment of the angular position of the bracket 33 with respect to the adjusting plate 31 the positions of the adjusting plate 31 provided by the openings 44, 45 and 46 will provide adjustment to compensate for a variety of standard panel slopes.

The brackets 33 and 40 are substantially similar. The bracket 40 has an opening 50 therein through which the portion 39 of the stud 20 extends and which corresponds to the opening 35 in the bracket 33. Bracket 40 also has an opening 51 therein which corresponds to the opening 36 in the bracket 33 and is for the accommodation of a pin or locating means such as 35'. In addition, the brackets 33 and 40 have integrally formed hooks 52 and 53, respectively, on one side thereof and integrally formed lugs 54 and 55 respectively, on the other side thereof. The hooks 52 and 53 extend through openings 56 and 57, respectively, in clamping members or straps 58 and 59. The hooks 52 and 53 secure one end of each of the clamping members or straps 58 and 59, respectively, to the brackets 33 and 40. The other ends of the clamping members or straps 58 and 59 are secured to the brackets 33 and 40 by screws 60 and 61 that extend through openings 62 and 63, respectively, in the straps 58 and 59 and are threaded into threaded openings 64 and 65 in the lugs 54 and 55, respectively. The brackets 33 and 40, together with their respective straps or clamping members 58 and 59 provide clamps for holding mercury tube switching elements such as 68 and 69 in Figs. 4 and 5. The mercury tube switching elements 68 and 69 may be any standard type of mercury tube switch in which the movement of a quantity of mercury makes and breaks a circuit between a pair of contacts. In this type of switch the angular disposition and movement of the mercury tube switching element is important since it controls the making and breaking of the circuit by controlling the movement of the mercury. Where two mercury tube switching elements are used, as shown in Figs. 4 and 5, the relative angular positions of the mercury tube switching elements control the relative time of making and breaking the circuits controlled by the switching elements.

The operating member 29 includes a projecting operating lever 70 having a handle 71 thereon that is preferably made of insulating material such as molded phenol-fibre. The operating member 29 also preferably includes an integral cam surface 72 and shoulders 73 and 74 displaced from the opening 28. The channel member 75 is secured to the base or mounting bracket 20 by rivets such as 76 that extend through openings 77 and 78 in the channel member 75 and base or mounting bracket 20, respectively. A ball 80 is slidably mounted in a channel portion 81 of the channel member 75 and is urged into engagement with the cam surface 72 by a spring 82 that is disposed between the ball 80 and the tang 83 on the channel member 75.

In the form of the switch shown in Figs. 1 to 5, inclusive, the cam surface 72 has a depression or indentation 85 and is convexly curved at 86 and 87 on each side of the depression or indentation 85 so that the ball 80 urges the operating member 29 toward a position in which it rests in the indentation or depression 85. With the convex cam surfaces 86 and 87 on each side of the depression or indentation 85, the operating member 29 is biased toward a central position and is operable in either direction to two positions from that central position. This form of cam is particularly desirable where two mercury switching elements such as 68 and 69 in Figs. 4 and 5 are controlled by the operating member 29. With such a cam both of the mercury switching elements may be in the circuit breaking position in the normal position of the operating member 29 and the operating member may be moved to either one of its other positions to effect closing of a circuit by either one of the mercury switching elements.

In either of the operated positions, such as that indicated at 71a, by the dot and dash lines in Figs. 4 and 5, the shoulders 73 and 74 engage the channel member 75 to stop movement of the operating member in either direction. Referring particularly to Figs. 6 and 7 reference numerals like those previously used designate similar parts. The switch shown in Figs. 6 and 7 is similar to that shown in Figs. 1 to 5, inclusive, except that a cam surface 100 having a projecting mid-portion 101 replaces the cam surface 72 of the switch shown in Figs. 1 to 5 inclusive. With a cam surface such as that shown in Figs. 6 and 7 at 100, the switch operating member 29 is biased to the position to which it was last operated and remains in that position until shifted by manual operation. It is, therefore, apparent that the switch shown in Figs. 6 and 7 has two operated positions as indicated in full lines at 71 and in dot and dash lines at 71b.

In the modified form of my switch, which is shown in Figs. 8 to 11, inclusive, reference numerals like those previously used also designate similar parts. In this particular switch the operating member 29, the adjusting plate 31 and a plate 110 that is interposed between the operating member 29 and the adjusting plate 31 are secured in position on a stud or similar rotatably mounted member by a screw 111. The adjusting plate 31 is secured in its preadjusted position by the screw 47 which is threaded into the plate 110, rather than into the operating member 29 as in the forms shown in Figs. 1 to 7, inclusive. There is preferably slight clearance at 113 between the plate 110 and the op-

erating member 29 so that the operating member is movable relative to the plate 110 and adjusting plate 31. A projecting lug 112, that is preferably integral with the plate 110, extends through a slot 115 in the operating member 29 and engages the ends of that slot when the operating member 29 is manually moved; the end of the slot engaged depending upon the direction of movement of the operating member. A second lug 116 that is preferably integral with the plate 110 and offset from the plane of the plate 110 carries a roller 117 that is rotatably mounted on a pin 118. The roller 117 engages a biasing spring 119 which acts as a resilient cam surface and has convexly curved portions at 120 and 121 for effecting quick or snap movement of the plate 110, adjusting plate 31 and the switching elements such as 68 and 69 to and from the circuit making and breaking positions. The biasing spring 119 is preferably backed and reinforced by a resilient leaf spring 122, both of which springs are secured in position by one of the screws 25 that holds the switch support bracket in position with respect to the panel 24.

When the operating member 29 is moved in one direction, as for example to the left from the position shown in Fig. 8, the lug 112 engages the end of the slot 115, to move the plate 110 therewith. This movement of the plate 110 is resisted by the biasing spring 119 until the roller 117 reaches the hump of the curved portion 120 after which the biasing spring 119 assists the movement of the plate 110 and effects quick or snap movement thereof, regardless of the speed of continued movement of the operating member 29. The slot 115 provides sufficient play or lost motion to allow the plate 110 to move with quick or snap action under the influence of the biasing spring 119, after the hump of the curved portion 120 has been passed. In moving the switch in its other position the lug 112 engages the other end of the slot 115 and the biasing spring 119 again resists movement of the plate 110 until after the hump of the curved portion 120 has been passed. The curved portion 121 of the biasing spring 119 improves the resilience and operating characteristics of the biasing spring.

In the switch shown in Figs. 8 to 11, inclusive, a cam surface 125 co-operates with the spring urged ball 80 and has a concavely curved mid-portion so that the operating member 29 is normally biased to a mid-position, such as that indicated in Figs. 8 and 9. The biasing force provided by the ball 80 in engagement with the cam surface 125 directly controls the normal position of the operating member 29 while the biasing force of the spring 119 directly controls the position of the adjusting plate 31 and intermediate plate 110, as well as the movement thereof.

In the switch shown in Figs. 8 to 11, inclusive, the adjusting plate 31 has projecting tabs 127 and 128 that are preferably offset from the rest of the surface of the adjusting plate to avoid engagement with other parts of the switch in the normal operating movement thereof. Brackets 129 and 130, that are preferably of the same construction as the brackets 33 and 40, are secured to the tabs 127 and 128, respectively, by rivets 131 and 132, or other suitable fastening means. As in the case of the brackets 33 and 40, the brackets 129 and 130 are pre-adjusted to a particular and fixed angular position with re-

spect to the adjusting plate 31. Each of the brackets 129 and 130 is adapted to co-operate with a suitable strap, such as the straps 58 and 59 in Fig. 1, to provide a mounting clamp for a mercury switch element. By this construction the switch shown in Figs. 8 to 11, inclusive, is adapted to carry two mercury switch elements 68 and 69 on one side of the switch, while the switch shown in Fig. 1 carries the mercury switch elements on opposite sides of the switch operating mechanism. Like the switch shown in Fig. 1, the normal sequence and time of operation of the mercury switches are controlled by the relative angular positions of the brackets 129 and 130, with respect to the adjusting plate 31. Adjustment is made to compensate for the angular disposition of the mounting panel 24 by adjustment of the position of the adjusting plate 31 which is determined and secured by the screw 47.

While I have illustrated and described herein a preferred embodiment of my invention, many modifications may be made without departing from the spirit and scope of the invention, and I do not desire or intend to be limited to the precise details set forth but do desire to avail myself of all changes within the scope of the appended claims.

What is claimed as my invention is:

1. A switch comprising, in combination, a base having an opening therein, a stud rotatably mounted in said opening in the base, an operating member secured to the stud and rotatable with respect to the base, an adjusting plate mounted on the stud and rotatable with respect to the operating member, means securing the adjusting plate in fixed angular relation with respect to the operating member, clamp means secured to each end of the stud in angularly preadjusted positions with respect to the adjusting plate, and means comprehending liquid circuit making and breaking elements secured in the clamp means and operable to circuit making and breaking positions by rotary movement of the operating member.

2. A switch comprising, in combination, a base, means rotatable with respect to the base and secured thereto, an operating member rotatably supported by said means, means angularly adjustable with respect to the operating member, means for securing the second mentioned means in a fixed angular position with respect to the operating member, a plurality of clamps secured to and adjustable with the second mentioned means, a mercury switch element carried by each of said clamps for movement with the operating member, each of said mercury switch elements having circuit making and breaking positions, and cam means integral with operating member and normally biasing the operating member to a position intermediate the extremities of movement thereof and such that the mercury switch elements are in the circuit breaking position, said clamps being so angularly disposed with respect to each other and with respect to the operating member that movement of the operating member in one direction moves certain of the mercury switch elements to circuit making position and movement of the operating member in the other direction moves certain other of the mercury switch elements to the circuit making position.

ERNST WALTER RICKMEYER.
